UNITED STATES PATENT OFFICE.

OLUF TYBERG, OF BROOKLYN, NEW YORK.

TYPE-WRITING MACHINE.

SPECIFICATION forming part of Letters Patent No. 749,002, dated January 5, 1904.

Application filed March 9, 1899. Serial No. 708,424. (No model.)

To all whom it may concern:

Be it known that I, OLUF TYBERG, a citizen of the United States, residing in the borough of Brooklyn, city of New York, State of New York, have invented certain new and useful Improvements in Type-Writing Machines, of which the following is a specification.

In an application filed by me May 8, 1897, Serial No. 635,681, I have shown a broadly novel organization wherein a wheel continuously revolving about a normally stationary axis has, when desired, imparted to it a bodily motion in a direction opposite to that in which the impression side of the wheel is traveling. The resultant effect of this momentary composite motion is that the character on the wheel selected to be printed from is momentarily maintained at the printing-point.

The machine herein described operates upon the same general principle; and the present invention comprehends new and useful ways of controlling the operation of the continuously - revolving wheel, taking impressions therefrom, and effecting the required operations of a type-writing machine.

In another application filed by me March 9, 1899, Serial No. 708,423, I have shown a type-writing machine more nearly resembling that disclosed herein than does the machine disclosed in my application first above-mentioned, and in said second application I have shown and claimed, broadly or generically, certain parts of the organization disclosed in the present case.

In the accompanying drawings, Figure 1 is an elevation of the left-hand end of the machine; Fig. 2, a plan view thereof, partly in section, on the line 2 2 of Fig. 1, with the driver partly broken away; Fig. 3, a front elevation, partly in section, on the line 3 3 of Fig. 1; Fig. 4, a detail view showing the essential parts of the carriage - feed devices; Fig. 5, a similar view of the same parts in a different position. Figs. 6, 7, 8, 9, and 10 are similar views showing in different positions a finger-key, a star or toothed wheel carried thereby, a driver that operates the wheel, and a swinging lever or frame operated by the wheel to so control the type-wheel as to maintain the selected character thereon momentarily at the printing-point.

As in my prior applications I employ a continuously - acting driver and as I prefer to use a rotary driver, I have shown a cylindrical driver 1, whose shaft or trunnions 2 2 have their bearings in the ends or vertical side plates 3 3 of the machine. This driver may be continuously rotated by any suitable motor located upon the stand of the machine 55 and to this end may be provided with a driving-pulley placed upon its right-hand end, as indicated in Fig. 3. This driver is a cammed, ribbed, or toothed driver and is shown as having a series of projections 4, extending spirally from one end to the other around its circumference. Mounted upon the left-hand end of the shaft or trunnion 2 of the driver is a rocking frame 3, having two parallel parts 6 6, extending toward the rear of the machine 60 and in which the type-wheel shaft 7 has its bearings. The gear-wheel 8, keyed to the driver trunnion or shaft between the parts 6 6 of the rocking frame, meshes with a corresponding gear 9, keyed to the type-wheel shaft. 65 As shown, these gears are of equal diameter, and the type-wheel shaft and the driver revolve at the same speed. The type-wheel 10 is shown as having two series of characters thereon and as connected to the type-wheel 8c shaft by a spline or feather connection 11, which permits the wheel to slide axially to bring either series of characters thereon opposite the printing-point. One series—that to the right and consisting merely, for illustrative purposes, of the Arabic numerals—is normally opposite the printing-point, and the wheel may be shifted endwise to the left, as hereinafter described, to bring the other series of characters opposite the same point, 70 this latter series being shown merely for illustrative purposes as consisting of the Roman numerals. But ten characters in each series on the wheel and ten corresponding finger-keys have been shown. The requisite number of characters for a type-writing machine would mean merely the duplication of parts shown in the drawings and fully described below.

The downwardly-extending arm 12, forming 100 part of the rocking frame, is connected by a link 13 with a pivoted hammer 14, arranged at the rear of the machine, and also by a link 15 to the lower end of a radial arm 16,

connected with a rock-shaft 17, mounted in bearings in the side or end plates of the machine. From this rock-shaft arms 18 extend toward the front of the machine in a plane below the type-wheel and driver and carry a transverse plate or bar 19. If now the bar 19 be momentarily raised, a movement would be imparted to the type-wheel, through the arm 16, link 15, arm 12 of the rocking-frame 10 and side plates 6 6 of that frame, and such motion would be a downward one, the normal axis X of the type-wheel being carried down to the point Y, as indicated in Fig. 1. The rotation of the type-wheel being in the 15 direction indicated by the arrow, this bodily movement of the axis of the wheel from X to Y is in a direction opposite to the rotation of the rear or impression side of the type-wheel, and any character thereon selected to 20 be printed from will for a moment be maintained at the printing-point, when an impression may be taken therefrom. In the particular organization shown the movement of the rocking-frame that carries the type-wheel 25 axis through the arc X Y also operates the hammer 14, through the link 13, to take an impression from the character then momentarily maintained at the printing-point. The means for effecting this behavior of the type-wheel will now be described.

The key-levers 20 are respectively pivoted upon a cross-bar 21, and their movement is limited by upper and lower cross-plates 22 23. Each key-lever is maintained in its normal 35 elevated position by a vertical plate-spring 24, formed near its end with a lateral wedge 25, that works against the correspondingly wedge-shaped end of the lever—that is to say, when the key is in the normal elevated position, as shown in Fig. 6, the lower inclined face of the spring rides upon the upper inclined face of the end of the lever and holds the outer end of the key-lever raised. When a key is depressed, the upper inclined face of 40 the spring bears against the lower incline of the end of the lever and forces it upward to the limit of the movement of the lever until the parts are restored to the normal position, as will now be described.

50 Loosely mounted near the end of each key-lever is a star-wheel 80, that shown having five teeth or projections arranged in suitable relation to the driver 1, rocking frame or plate 19, and fixed stop 26, all as shown in 55 Fig. 6. If now the lever be depressed, as shown in Fig. 7, the angle formed by the inclined faces at its end rides past the corresponding angle of the spring 24, and the upper inclined face of the spring then acting 60 upon the lower inclined face of the end of the lever completes the upward movement of the inner end of the lever and projects the star-wheel into the path of the corresponding projection 4 on the driver, as 65 shown in Fig. 8. During this movement the star-wheel is prevented from turning in either direction by the end face of the transverse

bar 19 and the fixed stop 26 and is presented in such relation to the driver that a radial line from the axis of the driver to the axis 70 of the wheel bisects the space between the two teeth of the wheel contiguous to or then in contact with the plane circumferential face of the driver. The projection 4 on the driver now comes against one of the teeth of 75 the star-wheel and partially rotates it, as seen in Fig. 9, the effect being that the following tooth on the wheel comes against the under face of the transverse plate 19 and moves it upwardly, thus effecting the traverse of the axis 80 of the type-wheel through the arc X Y, thereby maintaining the character on the wheel corresponding to the key momentarily at the printing-point and also actuating the hammer to take an impression therefrom. At 85 the same time the end of the tooth of the wheel against which the projection 4 on the driver is working is of necessity forced downward, as appears in Fig. 9, and the wedge-shaped end of the lever is carried below the wedge 25 of the spring. As the movement is being completed, as indicated in Fig. 10, the outer end of the finger-key rises, a tooth of the wheel comes against the fixed stop 26, and the transverse plate 19 falls 90 behind the tooth that has lifted it and the parts again assume their normal positions, the front edge of the plate 19 and the fixed stop 26 preventing the rotation of the wheel in either direction. A spring 27, having one 100 end connected to the frame and the other to the pendent arm 12 of the rocking frame carrying the type-wheel, returns the rocking-frame and associated parts and the transverse plate 19 to their normal positions which 105 is determined by a stop 28 on the frame against which the arm 12 of the rocking frame abuts.

In the organization shown, since the type-wheel and driver rotate at the same speed, 110 there is upon the driver but one projection, tooth, or cam for each character in either series of characters on the type-wheel, and of course the projections are radially disposed, corresponding with the radial disposition of 115 the characters on the wheel. Any other appropriate relative speeds of the driver and type-wheel may of course be adopted and the projections on the driver be correspondingly arranged. Thus if the type-wheel made two 120 revolutions to one of the driver there would be two projections at opposite points on the driver for each character in either series of characters on the type-wheel. The type-wheel may be shifted endwise upon its shaft 125 to bring either series of characters opposite the printing-point in the following manner.

A shifting-key 29 is shown as an arm projecting horizontally from a rock-shaft 30, having a spring 31, tending to retain it in normal 130 position. This shaft rocks in bearings 32 32 and carries at its rear end an upwardly-extending arm 33, that lies in an annular groove or channel 34, formed in the sleeve of

the type-wheel. In Fig. 2 the shifting-key is shown depressed, and the series of Roman characters on the type-wheel therefore stand opposite the printing-point. The carriage 35, carrying the roll 36, may be of any ordinary construction. As shown, it consists of a rectangular frame having a rod 37, running in a guide 38 in a bracket 39, extending rearwardly and upwardly at the back of the frame and about opposite the type-wheel. It also has a vertical plate 40, running in the grooves of rolls 41, mounted on a transverse bar 42, extending across the rear of the frame.

The rack 43 is vertically arranged at the front edge of the carriage. The paper is indicated by Z and is passed down into a curved holder 44, mounted on and arranged below the carriage, and passes upward as lines are successively printed between the roller 36 and the front vertical edge 45 of the holder, which acts as a spring bearing against the face of the roll, the paper being fed upwardly in the construction shown by the manual turning of the roll 36. The feeding-pawl 46 is pivoted in the end of a vertical arm 47, extending upwardly from a rock-shaft 48, from which an arm 49 extends to the opposite end of the machine, where it is pivotally connected with a vertical rod 50, connected to the arm 51 of a plate capable of rocking on the trunnion or end of the shaft 2 of the driver, Figs. 4 and 5. On this trunnion or shaft there is a toothed or ratchet wheel 53, mounted to turn with it, and on the rocking plate 52 is pivoted a three-armed latch 54, one arm of which, 55, is formed with a hook and is adapted to engage the teeth of the wheel 53. The other arm, 56, of the latch when in the normal position extends upwardly into the path of a pin 57, carried at the end of an arm 58, extending upwardly from the rock-shaft 17. The other arm, 59, of the latch is adapted to be caught by a catch 60, pivoted on the plate 52. A stop 61 on the frame limits the movement of the rocking plate 52, and a stop 62 on the plate 52 limits the movement of the latch-arm 55 away from the wheel. As seen in Fig. 2, a spring 63 is applied to the pivot of the latch 54 and acts to hold its arm 55 away from the wheel 53. Similarly a spring 64 is applied to the pivot of the catch 60 and tends normally to move its upper or hooked end toward the arm 59 of the latch 54. When the tooth of a star-wheel carried by a finger-key acts upon the plate 19 to rock the shaft 17, and thus, as described, move the axis of the type-wheel through the arc X Y, the desired character is momentarily maintained at the printing-point and an impression taken therefrom. During this time the arm 58, projecting upwardly from the shaft 17, moves rearwardly, carrying with it the arm 56 of the latch 54 and moving its catch-arm into the path of a tooth of the wheel 53, which is approaching it, and causing the third arm of the latch to be engaged and locked by the catch 60. After the impression has been taken

the tooth on the wheel comes against the arm 55 of the latch and carries it and the plate 52 around with it, as shown in Fig. 5, thereby raising the rod or arm 50 and rocking the arm 47 toward the left, the pawl 46 thereon in engagement with the carriage-rack then advancing the carriage one step or space. When the desired extent of movement of these parts has been obtained, the inclined tail or end 65 of the catch 60 comes against a tripping-block 66, mounted on the side plate of the machine. The catch is thereby caused to move out of engagement with the latch 54, which by the action of its spring returns to its normal position, and the plate 52, and this plate, rod 50, arm 49, and rock-shaft 48, &c., are returned to normal position by the reaction of a spring 66, Fig. 1, applied to the rock-shaft.

I have illustrated in the drawings only what seems requisite to a clear comprehension of the invention and have omitted immaterial parts. Thus the spring-drum for controlling the carriage has not been shown nor a line-spacing mechanism, as these may all be of any ordinary or suitable kind. Similarly no space-key is shown. The spacing may be accomplished in any suitable way, a special key being of course provided. The arrangement may be such as that shown in my second application, Serial No. 708,423, filed March 9, 1899, above referred to, and which shows a type-writing machine of the general character of the machine herein disclosed.

It will of course be apparent to those skilled in the art to which this invention relates that the invention may be embodied in other forms, and I do not, therefore, limit myself to the details herein described except so far as such limitations are specifically expressed in the claims to thereby distinguish from the more generic claims contained in my second application before mentioned.

I claim as my invention—

1. The combination of a continuously-revolving type-wheel, a rocking part in which it is mounted, a device for rocking said part and normally connected therewith, a driver and a series of devices each actuated at will by the driver to operate said devices and thereby rock said parts to momentarily maintain a character on the wheel at the printing-point.

2. The combination of a continuously-rotating type-wheel, a movable part in which it is mounted, a device for operating such movable part normally connected therewith, a driver, and a series of devices each actuated at will by the driver to operate said device to move the part in which the type-wheel is mounted and thereby maintain a given character thereon momentarily at the printing-point.

3. The combination of a continuously-rotating type-wheel, a movable part in which it is mounted, a device for operating such movable part normally connected therewith, a

driver, a series of devices each actuated at will by the driver to operate said device to move the part in which the type-wheel is mounted and thereby maintain a given character thereon momentarily at the printing-point, and means for then taking an impression from such character.

4. The combination of a type-wheel continuously rotating about a normally stationary axis, a movable part in which the type-wheel is mounted, a device for moving said part normally connected therewith, a continuously-rotating cammed, ribbed or toothed driver, a series of devices each operated at will by the driver to actuate said device and move the part in which the type-wheel is mounted to thereby maintain a given character thereon momentarily at the printing-point.
5. The combination of a continuously-rotating type-wheel, a rocking frame in which it is mounted, a cammed, ribbed or toothed wheel continuously rotating upon an axis parallel with that of the type-wheel, means for rocking the frame normally connected with it, a series of devices each operated at will by the driver to actuate the means for rocking the frame and thereby maintain any given character on the type-wheel momentarily at the printing-point.
6. The combination of a continuously-rotating type-wheel, a rocking frame in which it is mounted, a cammed, ribbed or toothed wheel continuously rotating upon an axis parallel with that of the type-wheel, means for rocking the frame normally connected with it, a series of devices each operated at will by the driver to actuate the means for rocking the frame and thereby maintain any given character on the type-wheel momentarily at the printing-point, and a hammer operatively connected with the rocking frame to then take an impression from such character.
7. The combination of a continuously-rotating type-wheel, a rocking frame in which it is mounted, a rock-shaft with which the rocking frame is operatively connected, means for rocking the shaft to thereby rock the frame, a driver and a series of devices actuated at will by the driver to operate the means for rocking the shaft and thereby maintain a given character on the type-wheel momentarily at the printing-point.
8. The combination of a driver, a lever or finger-key, a toothed wheel mounted upon said lever and normally out of engagement with the driver but brought into engagement therewith to be operated thereby on the manipulation of the lever and mechanism operated by the wheel.
9. The combination of a continuously-revolving driver, a lever mounted adjacent thereto, a toothed wheel mounted to turn upon the lever and normally out of engagement with the driver but advanced toward the driver by the manipulation of the lever

and means for automatically completing the movement of the wheel toward the driver to bring it into engagement therewith to be driven thereby and mechanism operated by the wheel.

10. The combination with the continuously-revolving driver having projections thereon, a lever, a star-toothed wheel mounted on the lever, a stop 26 and a part 19, operating substantially as set forth.

11. The combination with the continuously-revolving toothed driver, a lever, a star-toothed wheel mounted on the lever whereby when the lever is initially depressed the wheel is moved toward the driver, means for automatically completing the movement of the wheel toward the driver to bring it into engagement therewith to be driven thereby, a stop 26 and a part operated by the wheel when actuated by the driver.

12. The combination of a lever having a wedge-shaped end, a spring having a similarly-shaped part coöperating with the inclined faces of the end of the lever to maintain it in either of two positions, a star-toothed wheel carried by the lever, mechanism operated by the wheel and a continuously-rotating driver that actuates the wheel, all coöperating substantially as set forth.

13. The combination of a driver, a rotatable toothed wheel capable of movement toward and from the driver and normally out of engagement therewith and a device for moving the wheel into engagement with the driver to be operated thereby and mechanism operated by the wheel.

14. The combination of a driver, a rotatable toothed wheel capable of movement toward and from the driver and normally out of engagement therewith, a device for initially or partially moving the wheel toward the driver and means for then automatically completing the movement of the wheel into engagement with the driver to be operated thereby and mechanism operated by the wheel.

15. The combination of a driver, a rotatable toothed wheel arranged adjacent thereto and normally out of contact therewith but adapted to be moved bodily into engagement with the driver to be operated thereby, and a lever or finger-key for moving the wheel into engagement with the driver and mechanism operated by the wheel.

16. The combination of a driver, a series of toothed wheels mounted adjacent thereto and normally out of engagement with the driver but adapted to be moved bodily to be brought into engagement therewith, a series of devices for moving said wheels respectively into engagement with the driver to be operated thereby, a continuously-revolving type-wheel and mechanism operated by either toothed wheel when actuated by the driver to move the type-wheel bodily and thereby maintain a given character thereon momentarily at the printing-point.

17. The combination of a continuously-ro-

tating driver, a series of finger-keys or levers, a series of devices mounted one upon each lever and normally out of contact with the driver but carried into engagement therewith by the depression of its lever, a continuously-revolving type-wheel, and mechanism for moving it bodily by either of said devices when actuated by the driver.

18. The combination of a continuously-rotating driver, a series of key-levers, a star-toothed wheel mounted upon each lever and normally out of engagement with the driver but brought into engagement with the driver on the depression of its lever, a continuously-revolving type-wheel and mechanism for moving it bodily in a direction opposed to the rotation of its impression side operated by either of said star-wheels when actuated by the driver.

19. The combination of a driver, a series of toothed wheels mounted adjacent thereto and out of engagement therewith but adapted to be moved bodily to be brought into engagement therewith, a series of devices for partially moving said wheels respectively into engagement with the driver to be operated thereby, means for then automatically completing the movement of the wheel to bring it into engagement with the driver, a continuously-revolving type-wheel and mechanism for moving it bodily operated by either toothed wheel and actuated by the driver.

20. The combination of a continuously-rotating carriage-feed toothed wheel, a pivoted part or plate, a carriage-feed pawl operatively connected with said pivoted part, a latch pivoted upon said plate or part and normally out of engagement with the toothed wheel but adapted to be thrown into engagement therewith, means whereby the latch is thrown into engagement with the wheel when the carriage is to be fed and means for disengaging the latch from the wheel when the feed of the carriage is completed.

21. The combination of a continuously-rotating carriage-feed toothed wheel, a rocking plate or part arranged adjacent thereto, a carriage, its rack, the carriage-feed pawl, operative connections between the pawl and said rocking plate or part, a pivoted latch pivoted upon said part and normally out of engagement with the toothed wheel but adapted to

be thrown into engagement therewith, means for throwing the latch into engagement with the wheel, a catch for holding it in such engagement and a tripping device for tripping the catch and releasing the latch when the required movement of the carriage has been effected.

22. The combination of a continuously-rotating type-wheel, the movable part or frame in which it is mounted, a continuously-rotating driver, a series of key-levers, means whereby when a given key-lever is depressed the part in which the type-wheel is mounted is moved to thereby maintain the corresponding character momentarily at the printing-point, the carriage, its rack, the feed-pawl, a pivoted rocking plate or part 52, a continuously-rotating toothed wheel, a latch pivoted on said part and adapted to be moved into engagement with the continuously-revolving toothed wheel, means for moving the latch into the path of the toothed wheel during the movement of the part in which the type-wheel is mounted, a catch for holding the latch in this position and a tripping device for releasing the catch from the latch when the feed movement of the carriage is completed.

23. The combination of the type-writer carriage and its rack, of a continuously-rotating toothed wheel, the carriage-feeding pawl or device, operative connections normally inactive or at rest between said device and the continuously-rotated toothed wheel, and means for at will, actuating such operative connections to feed the carriage.

24. A wheel having characters thereon, means for rotating it continuously, a rocking frame in which it is mounted, a driver, finger-keys, devices operated thereby to engage driver and rock said frame, in combination with means for taking an impression from the wheel, at a fixed or stationary printing-point by means of an impression device that does not follow the rotary movement of the wheel without arresting its rotation.

In testimony whereof I have hereunto subscribed my name.

OLUF TYBERG.
